By his Attorneys,

Inventor
James J. Dunne

C. A. Snow & Co.

UNITED STATES PATENT OFFICE.

JAMES J. DUNNE, OF WENONA, ILLINOIS.

DESIGN FOR A SHOW-CASE.

SPECIFICATION forming part of Design No. 20,154, dated September 9, 1890.

Application filed April 22, 1890. Serial No. 349,011. Term of patent 14 years.

To all whom it may concern:

Be it known that I, JAMES J. DUNNE, a citizen of the United States, residing at Wenona, in the county of Marshall and State of Illinois, 5 have invented a new and original Design for Show-Cases, of which the following is a specification.

The invention relates to a new and original design for show-cases.

10 The object of the present invention is to provide an ornamental and attractive case for exhibiting tobacco.

In the drawings, Figure 1 is a perspective view of a show-case illustrating my new design. Fig. 2 is a plan view. Fig. 3 is a side elevation.

15 The leading feature of my design is the show-case consisting of the Greek-cross top, the octagonal bottom, the vertical sides arranged in pairs and forming angles between them, and the doors arranged at each pair of sides.

20 Referring to the accompanying drawings, 1 designates the top of the show-case, which top is the shape of a Greek cross, and 2 designates a polygonal-shaped bottom.

25 3 designates vertical side pieces, which are connected to the top and bottom of the case and are arranged at right angles to the adja-

cent front edges of the said top and bottom, 30 and they have their inner vertical edges secured together, and they are arranged at right angles to each other in pairs. The vertical side pieces, which are arranged in pairs at right angles to each other, are parallel with 35 the adjacent side piece of the opposite pair and form the open faces 4 of the show-case, and they form between the faces 4 angular recesses 5. The edges of the Greek-cross-shaped top and the polygonal bottom are provided with moldings 6 and 7.

What I claim is—

The design for a show-case herein shown and described, the same consisting in the Greek-cross-shaped top, the octagonal bottom, the 45 parallel vertical sides arranged in pairs at the arms of the cross-shaped top and forming angular spaces between each pair, and the doors arranged at the end of the arms, as set forth.

50 In testimony that I claim the foregoing as my own I have hereto affixed my signature in presence of two witnesses.

JAS. J. DUNNE.
